(57) **CLAIM**

The ornamental design for an oral implant flag, as shown and described.

DESCRIPTION

FIG. 1 is a front view of an oral implant flag showing our new design.

FIG. 2 is a back view thereof.

FIG. 3 is a top end view thereof.

FIG. 4 is a bottom end view thereof.

FIG. 5 is a side view thereof.

FIG. 6 is a perspective side view demonstrating our new design; and,

FIG. 7 is a cut away view of FIG. 3 with a defining line as indicated from 7 to 7.
